UNITED STATES PATENT OFFICE.

LOUIS A. STATES, OF GASTONIA, NORTH CAROLINA.

GRATE.

1,387,871.

Specification of Letters Patent. Patented Aug. 16, 1921.

Application filed August 11, 1917. Serial No. 185,644.

To all whom it may concern:

Be it known that I, LOUIS A. STATES, a citizen of the United States, residing in Gastonia, county of Gaston, and State of North Carolina, have invented certain new and useful Improvements in Grates, of which the following is a specification.

This invention has reference to grates and it has for one of its chief objects the provision of an improved form of grate which is simple and economical in construction and which provides a maximum air circulation space and provides better combustion and more economical consumption of fuel, thus increasing general efficiency. Another object of the invention resides in the provision of a grate of the character specified in which the necessity for shaking the grate is eliminated, and in which the formation of slag, even with relatively poor fuel, hardly ever takes place.

My invention also contemplates the provision of a grate of such character that burning, buckling, sagging, and other distortions caused by over-heating are prevented.

In addition my invention makes it possible to have all of the grate bar units counterparts, any one of which can be readily replaced.

The foregoing, together with such other objects as may hereinafter appear, I obtain by means of a construction which I have illustrated in preferred form in the accompanying drawings, wherein—

Figure 1 is a plan view of a portion of a grate embodying my invention; Fig. 2 is a side elevation of one of the grate bar units; Fig. 3 is a section taken on the line 3—3 of Fig. 1; and Fig. 4 is a section taken on the line 4—4 of Fig. 1.

In carrying out my invention I build up the grate from a plurality of grate bar units A, preferably arranged in groups of three, secured together in a manner to be described.

Each grate bar unit comprises a supporting truss member 7 which is provided at each end with a flattened end portion 8, adapted to rest upon some suitable support in the fire box or furnace. A plurality of fire supporting stools or fingers 9 are cast integral with the truss member 7 and project above the top edge thereof in such manner as to support the fire bed out of contact with the truss member. These fingers are oblong in shape and extend transversely of the truss

member, and in length are about three times the width of the truss member. The fingers are wedge-shaped with the small ends down so as to provide jet-like vertical circulation spaces a between the fingers, the fingers being spaced apart a distance approximately equal to half their thickness. The end portions 8 are provided with laterally extending fingers 8' which are slightly longer than the fingers 9 and act as spacing members when the grate bars are assembled, to space apart the grate bars, so as to provide longitudinal air channels b, which in width correspond substantially to the spaces between adjacent fingers, the fingers 8' on the end members 8 being dimensioned to secure this result.

It will be observed that the end members 8 are of unequal length so that the fingers 9 approach one end of the grate bar more nearly than the other, as a result of which, when the individual units are assembled in reversed relation, the fingers of one grate bar will come opposite the spaces between the fingers of the adjacent grate bar, and so on. By this arrangement the transverse circulating channels c extending transversely of the grate, above the tops of the truss members, will be sinuous in character. This arrangement has many advantages, for it not only provides adequate circulation transversely of the grate but also prevents the formation of large gaps which would permit fuel to fall through the grate, such as would be the case if the fingers were arranged in alignment transversely of the grate as well as longitudinally.

About midway of the truss members and at other intervals on long grates are cast laterally extending projections 7', the upper ends of which are pointed, and the angle of inclination being greater than the angle of rest so that any ash which will work down past the fingers will be deposited in the ash pit. These extensions 7' have the same length as the fingers 8' and serve to space apart the truss members. Between the extensions 7' each truss member is apertured to receive a bolt 10, by means of which the groups of three grate bars are held together. Similar bolts are used at the ends as will be seen from inspection of Figs. 1 and 2. By this general arrangement the truss members are securely supported and will not warp or bend, as a result of which the

fingers are always maintained in proper spaced relation to provide the longitudinal air circulation channels *b*.

From inspection of the drawings it will be noted that the tops of the truss members which extend between the fingers *9* are pointed so that ash will be freely discharged into the ash pit. It will also be noted that the truss member, in alternate spaces, is carried nearer to the top of the fingers but not to such an extent as to completely interrupt the transverse air circulating channels *c*. By this arrangement the fingers are reinforced, which is of vital importance to the life of the grates, while at the same time adequate provision is made to accommodate the expansion of the metal contained in the stools under the head of the fire bed and to permit of what is technically termed the "growth" of the iron under the action of the continued heating and cooling effects in the regular service of a grate, and this without placing strain on the truss member proper.

It will also be noted that the truss members intermediate the top and bottom, and intermediate the fingers, are reinforced by diamond-shaped projections *7a*, which in addition to reinforcing the truss members act in the nature of air diffusion nozzles. Stated in other words, the vertical space between the truss members is contracted and then expanded, which assists in diffusing or spreading the air equally through all of the air passages at the sides and ends of the stools or fingers.

To further increase the stiffness of the truss members I provide each of them with a rib-like portion *7b* at the lower edge thereof, and to further assist in setting up free air circulation, I provide in each of them a plurality of openings *11* at points which are substantially intermediate the lower edges of the fingers and the lower edge of the truss member.

By the foregoing improvements I am enabled to construct a grate which is very economical in the consumption of fuel, is productive of far more nearly perfect combustion, and which it is not necessary to shake, as I have found by actual experience. In this connection it is also to be observed that even with poor fuel the formation of clinkers hardly ever occurs. At the same time I have found that a grate of this construction, in comparison to standard grates now being used, lasts considerably longer. I have removed grates of this type which have been in service over ten thousand consecutive working hours, and found them in substantially the same condition as when installed, without appreciable loss of metal and with no bending or distortion. Fur-

thermore, I have also found that a far greater percentage of ash sifts through naturally, so that it is only necessary to use a fire hoe to clean the fire.

I attribute the foregoing advantages in great part to the arrangement whereby I secure such a large percentage of air space. Thus, for example, in the general construction shown, if I were to use fire supporting stools or fingers $\frac{5}{8}$ " x $1\frac{1}{8}$ ", with a $\frac{3}{8}$ " air space between fingers, I obtain a total percentage of air space of 50% of the grate area. If $\frac{1}{16}$ " x $1\frac{9}{16}$ " stools, with a $\frac{7}{16}$ " air space, be utilized, I obtain 56% air space; and if $\frac{1}{2}$ " x $1\frac{1}{2}$ " stools, with $\frac{1}{2}$ " air space, be utilized, I obtain 62 $\frac{1}{2}$ % air space. Notwithstanding that I secure such a large percentage of air space, the grates are amply strong and rugged, as is evidenced by the long life of the grates. It will be obvious that with such increased air space more nearly perfect combustion will be obtained while at the same time the metal will be relatively cooled, and warping and distortion prevented. It is also to be observed that even with this large air space, at no point is there formed any opening of such size as will permit live or unconsumed fuel to fall through the grate.

As previously pointed out, ample provision is made for reinforcing the stools and also for accommodating the expansion of the metal contained in the stools when they are heated, and to permit of the growth of the iron under the continued heating and cooling effects in service, without strain on the truss member proper, and this without diminution of the air space.

In addition to the foregoing, it is to be noted that the grate is simple and economical, in that each grate member is a counterpart of the other, which simplifies and cheapens manufacture, as well as maintenance, for new elements can be readily inserted to replace worn ones.

I claim:

1. A grate comprising a plurality of grate bar members each comprising a truss provided with a plurality of stools spaced apart and projecting thereabove, the truss member extending more nearly to the top in the spaces between certain of the stools than between others whereby to reinforce the stools.

2. A grate bar comprising a truss provided with a plurality of stools spaced apart and projecting thereabove, the truss member extending more nearly to the top in alternate spaces between the stools whereby to reinforce the stools.

In testimony whereof I have hereunto signed my name.

LOUIS A. STATES.
